US00D709059S

(12) **United States Design Patent**
Kim et al.(10) **Patent No.:** **US D709,059 S**
(45) **Date of Patent:** **** Jul. 15, 2014**(54) **CASE FOR ELECTRONIC DEVICE**(71) Applicant: **Otter Products, LLC**, Fort Collins, CO (US)(72) Inventors: **Michael H. Kim**, San Diego, CA (US); **Dennis J McCray**, San Diego, CA (US); **Jeffrey M. Borra**, Poway, CA (US)(73) Assignee: **Otter Products, LLC**, Fort Collins, CO (US)(**) Term: **14 Years**(21) Appl. No.: **29/465,052**(22) Filed: **Aug. 23, 2013**(51) LOC (10) Cl. **14-03**

Primary Examiner — Carla Jobe Wright

(57) **CLAIM**

The ornamental design for a case for electronic device, as shown and described.

DESCRIPTION

FIG. 1 is a front isometric view of a case for electronic device showing our new design;

FIG. 2 is a rear isometric view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The dash-dash-dash broken lines depict unclaimed environment. The broken lines form no part of the claimed design.
